UNITED STATES PATENT OFFICE.

LOUIS N. D. WILLIAMS, OF ASHBOURNE, PENNSYLVANIA, ASSIGNOR OF ONE-HALF TO ROBERT W. SCOTT, OF PHILADELPHIA, PENNSYLVANIA.

KNITTING-MACHINE.

SPECIFICATION forming part of Letters Patent No. 727,522, dated May 5, 1903.

Application filed December 14, 1901. Serial No. 85,934. (No model.)

To all whom it may concern:

Be it known that I, LOUIS N. D. WILLIAMS, a citizen of the United States, residing in Ashbourne, Montgomery county, Pennsylvania, have invented certain Improvements in Knitting-Machines, of which the following is a specification.

The object of my invention is to so construct a knitting-machine as to provide fine-gage grooves or guides for the needles, hooks, or other yarn-engaging elements at the edge of the needle-carrier where the stitches or loops are drawn without the necessity of providing grooves of like fine gage for the guidance of the stem or shanks of said needles, hooks, or other yarn-engaging elements.

When my invention is used in connection with a machine for producing fabrics having a fleecing-yarn inserted therein, it permits of the use of one and the same cam-carrier for both the needle-operating cams and for those which operate the hooks which engage the fleecing-yarn.

In the accompanying drawings, Figure 1 is a vertical sectional view of sufficient of an ordinary form of rib-knitting machine to illustrate the application of my invention thereto. Fig. 2 is a face view of part of the needle-cylinder of the machine. Fig. 3 is an enlarged sectional view of the upper portion of said needle-cylinder. Fig. 4 is a top or plan view of the same. Fig. 5 is a view similar to Fig. 2, but illustrating another means of carrying out my invention; and Figs. 6 and 7 are views illustrating a special feature of my invention.

I have shown in the drawings in order to illustrate my invention part of a rib-knitting machine intended to produce a fabric having a fleecing-yarn combined therewith, 1 representing part of the needle-cylinder of the machine; 1^a, the cylinder-needles; 2, part of the needle-dial; 2^a, the dial-needles; 3, part of the cam-cylinder, and 4 part of the dial cam-plate, the cam-cylinder having a suitable cam structure 5 for imparting vertical reciprocation to the cylinder-needles 1^a and the dial cam-plate having a cam structure 6 for imparting horizontal reciprocation to the dial needles 2^a in the usual manner.

It has not been deemed necessary to illustrate a complete machine, as the machine so

far as its general structure is concerned may be similar to many of those now in common use.

With the needles of the cylinder are alternated hooks 7 for engaging the fleecing-yarn, it being understood that the knitting-yarn and the fleecing-yarn are intended to be fed to the machine by separate feeders in the usual way. The hooks 7 are reciprocated by a cam structure 9 on the cam-cylinder 3, so as to rise, engage the fleecing-yarn, and draw loops of the same between the stitches formed by the cylinder-needles, the upper ends of the hooks 7 being guided in grooves at the top of the needle-cylinder, which grooves alternate with the grooves wherein the upper ends of the cylinder-needles are guided. The upper end of the cylinder has, therefore, to be cut twice as fine as if the hooks 7 were not employed, and in making machines of fine gage it is both difficult and expensive to provide between the adjoining grooves walls of sufficient thickness, for the grooves must not only be wide enough to permit of the passage of the needles and hooks, but must also permit the latter to draw down the stitches of knitting-yarn or loops of fleecing-yarn below the tops of said walls. In machines of fine gage I therefore form the grooves for the guidance of the needles and hooks by means of trough-shaped strips 10, preferably of thin sheet metal bent into the trough form, and which I term "quills," the bases of these quills being let into grooves at the top of the cylinder and secured therein by soldering, brazing, or in any other available manner, so that the space between the projecting flanges of each quill will form a guide for a needle, and the space between the flanges of adjoining quills will form a guide for a hook, or vice versa, or when the invention is applied to a plain-knitting machine each space will serve as a guide for the hooked upper end of a needle. The quills can be made of sheet metal and yet still possess the requisite strength, the U form rendering them extremely rigid. They can, however, be formed by milling or swaging a wire or strip of metal, and, if desired, their flanges can be thicker at the bases than at the tops—as shown, for instance, at 10^a and 10^b in Figs. 6 and 7—so as to snugly guide the

needles or hooks and yet provide spaces at their upper ends for the drawing of the loops or stitches.

In order to avoid the fine cutting of the body of the cylinder for the reception and guidance of the stems or shanks of the needles and hooks, I provide for the guidance of the shank of each needle and the shank of its adjoining hook in one and the same groove, either by disposing one shank below the other in the groove, as shown in Figs. 1 and 2, or by disposing the two shanks side by side in the groove, as shown in Fig. 5, thereby reducing by one-half the number of grooves and intervening walls which would be required if the ordinary method of manufacture was adopted. This involves the lateral bending of the outer or acting end of the needle or hook, or both, so that the operative ends of the same will alternate and will be equidistantly disposed around the top of the cylinder. In the present instance I have shown the hooks 7 as the bent elements, the lateral bend being shown at 11 in Fig. 2. Where the elements are disposed one below the other in the groove, the inner one will also have to be bent forwardly at the outer end—as shown, for instance, at 12 in Fig. 1—this bend being also shown in the hook 7; but the lateral bend may be formed in one of the elements and the forward bend in the other, if desired, or where the shanks of the needle and hook are disposed side by side the lateral bend only will be necessary, as shown in Fig. 5, and this bend may be formed either in the hook or in the needle, or in the case of a plain-knitting machine the bend may be formed in either needle of the pair or a lesser bend in each needle of the pair. The butts of the needles and hooks are of course arranged in different planes, so that the needle and hook operating cams can likewise be disposed in different planes and will not interfere with each other. The same principle may be adopted in connection with reciprocating web-holders, and in machines in which web-holders separate from the needle-carrier are used the needles, hooks, or other yarn-engaging elements may be guided between said web-holders instead of by grooves formed in the outer portion of the needle-carrier.

Although my invention is especially designed for application to rib-knitting machines which employ a fleecing-yarn and in which hooks for engaging said yarn alternate with the needles, it is not limited in its application to such machine, but may be adapted to plain-knitting machines as well. Hence in some of the claims I have used the term "yarn-engaging elements" as indicating either needles, hooks, web-holders, or the like, and it will be evident that the disposal of the yarn-engaging elements which I have shown in connection with the cylinder can be adopted in connection with the dial as well, the invention, moreover, being applicable to machines in which the needle-cylinder and

dial are stationary and the cam-cylinder and cam-plate are intended to rotate, as in the drawings, or to machines in which the reverse construction is adopted—that is to say, in which the needle-cylinder and dial rotate and the cam-cylinder and dial cam-plate are stationary—the use of the quills for forming the grooves at the outer end of the needle-carrier being applicable to single-knitting machines as well as to rib-knitting machines and the various features of my invention being capable of use in straight machines as well as circular machines and in machines using spring-beard needles as well as machines using latch-needles.

In order to provide for the free passage of the fleecing-loops with the fabric as the latter is drawn down from the needles, I cause the quills 10 to project above the upper end of the needle-cylinder, the top of the latter being so far below the tops of the quills as to provide sufficient clearance between the same and the dial for the unobstructed passage of the loops of fleecing-thread between the two.

While I have shown the grooves in the body of the needle-carrier as adapted for the guidance of two adjoining yarn-engaging elements, they may receive three or more of the same, if desired, the number of grooves at the end of the carrier being correspondingly multiplied.

I am aware of the patent of Joseph Heginbothom, No. 182,822, dated October 3, 1876, in which the needles were disposed side by side with interposed sliding bits, fixed separator-strips being disposed at intervals, and hence I do not claim any such construction.

Having thus described my invention, I claim and desire to secure by Letters Patent—

1. A knitting-machine-needle carrier having the guide-grooves at its outer end formed by trough-shaped strips secured to said needle-carrier, substantially as specified.

2. A knitting-machine-needle carrier having the guide-grooves at its outer end formed by trough-shaped strips secured to said needle-carrier, the flanges of said strips being wider at the bases than at the tops, substantially as specified.

3. A knitting-machine-needle carrier having the grooves at its outer end formed by means of trough-shaped strips let into recesses in the needle-carrier and secured therein, substantially as specified.

4. A knitting-machine-needle carrier having the guide-grooves at its outer end formed by strips of sheet metal bent into trough shape and secured to said needle-carrier, substantially as specified.

5. A knitting-machine-needle carrier having secured to its outer end trough-shaped strips, each forming a guide-groove between its projecting flanges, said strips being spaced so as to form other guide-grooves between adjoining strips, substantially as specified.

6. A knitting-machine needle, hook, or other

yarn-engaging element having its hooked end and butted shank formed in one piece and having between its outer yarn-engaging end and that portion of the stem or shank upon 5 which the butt is formed, two bends, the first being a lateral bend with respect to the hook, and the other a forward bend, substantially as specified.

7. The combination of a knitting-machine-needle carrier having two or more times as many grooves in its outer portion as in that portion which guides the stems or shanks of the yarn-engaging elements, with said yarn-engaging elements disposed in pairs or groups, 10 the members of each pair or group being independent of each other throughout and the stems or shanks of each pair or group being guided in one and the same groove of the needle-carrier, but their outer or yarn-engaging ends being guided in separate grooves in the outer portion of the carrier, the ends of said grooves projecting beyond the ends of the yarn-engaging elements when the latter are retracted, substantially as specified.

25 8. The combination of a knitting-machine-needle carrier, with yarn-engaging elements disposed in pairs or groups, the members of each pair or group being independent of each other throughout, and the stems or shanks of each pair or group being guided in one and the same groove of the needle-carrier, but their outer or yarn-engaging ends being separately guided in grooves disposed side by side at the outer end of the carrier, one or 30 more of the pairs or groups of yarn-engaging elements being bent laterally at the point between the inner and outer guides, substantially as specified.

35 9. The combination of a knitting-machine-needle carrier having two or more times as many grooves disposed side by side in its outer portion as in that portion which guides the stems or shanks of the yarn-engaging elements, with said yarn-engaging elements disposed in pairs or groups, the members of each pair or group being independent of each other throughout, and the stems or shanks of each pair or group being guided in one and the same groove of the needle-carrier, but their outer or yarn-engaging ends being guided in separate side-by-side grooves in the outer portion of the carrier, one or more of the pair or group of said yarn-engaging elements being bent laterally in the space between the 45 two grooved portions of the carrier, substantially as specified.

50 10. The combination of a knitting-machine-needle carrier, with yarn-engaging elements disposed in pairs or groups, the members of each pair or group being independent of each other throughout, and the stems or shanks of each pair or group being guided in one and the same groove of the needle-carrier, but their outer or yarn-engaging ends being separately guided in grooves of the needle-carrier, 55 some of said yarn-engaging elements being

bent forwardly at a point between the inner and outer guides, substantially as specified.

11. The combination of a knitting-machine-needle carrier having two or more times as many grooves disposed side by side in its outer portion as in that portion which guides the stems or shanks of the yarn-engaging elements with said yarn-engaging elements disposed in pairs or groups, the members of each pair or group being independent of each other throughout, and the stems or shanks of each pair or group being guided in one and the same groove of the needle-carrier, but their outer or yarn-engaging ends being guided in 70 separate side-by-side grooves, in the outer portion of the carrier, some of said yarn-engaging elements being bent forwardly in the space between the two grooved portions of the carrier, substantially as specified. 75

12. The combination of a knitting-machine-needle carrier, with yarn-engaging elements disposed in pairs or groups, the stems or shanks of each pair or group being guided in one and the same groove of the needle-carrier, 80 but their outer or yarn-engaging ends being separately guided in grooves of the needle-carrier, one of said pair or group of yarn-engaging elements being bent both laterally and forwardly at a point between the inner and 85 outer guides, substantially as specified.

13. The combination of a knitting-machine-needle carrier having two or more times as many grooves disposed side by side in its outer portion as in that portion which guides the stems or shanks of the yarn-engaging elements, with said yarn-engaging elements disposed in pairs or groups, the stems or shanks of each pair or group being guided in one and the same groove of the needle-carrier, but 90 their outer or yarn-engaging ends being guided in separate side-by-side grooves in the outer portion of the carrier, one of said pair or group of yarn-engaging elements being bent both laterally and forwardly in the space 95 between the two grooved portions of the carrier, substantially as specified.

14. The combination in a rib-knitting machine, of a needle-carrier having twice as many grooves in the outer portion as in the lower or inner portion, knitting-needles and fleece-yarn-engaging hooks alternating with each other and each guided near its yarn-engaging end in one of the grooves at the outer end of the carrier, the ends of said grooves 100 projecting beyond the ends of the yarn-engaging elements when the latter are retracted, the stem or shank of a needle and the stem or shank of an adjoining hook being guided in one and the same groove in the lower or 105 inner portion of the carrier, substantially as specified.

15. The combination in a rib-knitting machine, of a needle-carrier having twice as many grooves disposed side by side in the 110 outer portion as in the lower or inner portion, knitting-needles and fleece-yarn-engaging

hooks alternating with each other and each guided near its yarn-engaging end in one of the grooves at the outer end of the carrier, the stem or shank of a needle and the stem or shank of an adjoining hook being guided in one and the same groove in the lower or inner portion of the carrier, and either or both being bent laterally in the space between the two grooved portions of the carrier, substantially as specified.

16. The combination in a rib-knitting machine, of a needle-carrier having twice as many grooves in the outer portion as in the lower or inner portion, knitting-needles and fleece-yarn-engaging hooks alternating with each other and each guided near its yarn-en-

gaging end in one of the grooves at the outer end of the carrier, the stem or shank of a needle and the stem or shank of an adjoining hook being guided in one and the same groove 20 in the lower or inner portion of the carrier, and each fleece-yarn-engaging hook being bent both laterally and forwardly in that portion which is between the two grooved portions of the carrier, substantially as specified. 25

In testimony whereof I have signed my name to this specification in the presence of two subscribing witnesses.

LOUIS N. D. WILLIAMS.
